UNITED STATES PATENT OFFICE.

HENRY CLAUDE PRIVETT, OF LOS ANGELES, CALIFORNIA.

CONTINUOUS AGITATING COOKER.

1,226,593.

Specification of Letters Patent. Patented May 15, 1917.

Application filed May 27, 1914. Serial No. 841,283.

To all whom it may concern:

Be it known that I, HENRY CLAUDE PRIVETT, a citizen of the United States, residing at Los Angeles, in the county of Los Angeles and State of California, have invented a new and useful Continuous Agitating Cooker, of which the following is a specification.

This invention relates to cookers in which the substance to be cooked is stored in cans and cooked while in such cans, the cans being passed through cookers.

An object of the invention is to provide a cooker of this class in which a very high degree of temperature can be maintained.

Another object is to provide a cooker in which a large number of cans may be cooked simultaneously and in which each can will be fed into and removed from said cooker without interfering with any of the other cans in said cooker.

A still further object of the invention is to provide an arrangement whereby the cans are fed through the cooker at such a speed that the substance to be cooked will simultaneously be properly cooked and fed out so that they will be ready for the warehouse.

Another object of the invention is to provide an arrangement whereby the substance in the cans will be agitated while being cooked. To this end, the cans are carried through the cooker while on their sides and thus permitted to roll.

Another object of the invention is to provide an arrangement in which the cans are automatically fed into the cooker.

Another object of the invention is to provide a cooker having a conveyer to convey cans through a steam chest, which conveyer may be removed bodily from the steam chest for the purpose of repair, cleaning and the like.

The important features, capabilities and advantages of the invention will appear from the subjoined detail description of one specific embodiment thereof.

Figure 1 is a broken fragmental longitudinal section of the improved cooker embodying this invention and taken partly in mid-section and partly through the entrance and exit on line x^1-x^1 , Figs. 2, 3, 4 and 5. Cans are shown in position as they enter and leave the cooker.

Fig. 2 is a transverse section viewed from

irregular line x^2-x^2 , Figs. 1, 3 and 5. The cable is omitted and parts broken away for clearness of illustration.

Fig. 3 is a fragmental plan section viewed from irregular line x^3-x^3 , Figs. 1 and 2 illustrating the entrance and exit. Cans are shown in positions assumed during the course of travel through the cooker, while dot and dash lines indicate positions of cans leaving the cooker. For clearness of illustration the heating system is omitted in this view.

Fig. 4 is a plan view partly in section illustrating the heat containing chest together with its heating system. The frame work and conveyer are removed in this view and parts are broken away to expose otherwise hidden construction.

Fig. 5 is a fragmental sectional plan viewed from irregular line x^5-x^5 , Figs. 1 and 2, with portions of the heating system in place.

Fig. 6 is an enlarged cross-section through the track and conveyer showing a can in relative position, section is taken on line x^6-x^6 , Figs. 1, 3, 5 and 7.

Fig. 7 is an enlarged sectional detail of a portion of the inclined track and conveyer viewed from line x^7-x^7 , Fig. 6, together with a can shown in the course of travel.

Arrows on the various views indicate the direction of sight.

In the embodiment shown, there is provided a steam chest 1 having two side walls 2, 2, and a floor 3 and roof 4 properly secured to one another by suitable means and reinforced by a series of binding stays each composed of two side stays 5, 5, one along each of the side walls 2, 2 and top and bottom stays 6, 6 one along the floor and the other along the roof respectively, the side stays and adjacent top and bottom stays being secured to one another by reinforcing angle irons 7. The steam chest 1 may be supported in any suitable manner, in the present instance setting on transversely disposed beams 8. The front and rear ends of the chest are provided with doors hinged to the roof 4. A door 9 is provided for the rear end of the chest shown at the right side of Fig. 1, hinged at 10 to a reinforcing angle 11 extending around the roof floor and sides at the rear thereof, the edges of the door extending over upon the angle 11 and

secured thereto by suitable locking bolts 22, the upper portion of the door 9 being provided with an opening 12 to serve as an exit for the cans being conveyed through the entire cooker. A door 13 is provided for the front end of the chest being hinged at 14 to the reinforcing angle 15 extending around the roof, floor and sides at the front thereof, the edges of the door extending over upon the angle 15 and secured thereto by the locking bolts 22', an opening 16 being provided at the lower right-hand side of the door to serve as an entrance for the cans conveyed into the cooker. The opening 16 is provided with a chute 17 having a front deflector plate 18 and provided with straight sides 19 and a cover 20 hinged to the door 13, the chute being provided near the upper end of the deflector plate 18 with a small opening 21 just sufficient to admit a can. The doors 9 and 13 when in lowered or closing position are locked by the locking bolts 22, 22'.

The inclosing walls of the steam chest just described are formed of substantial material in the present instance shown as composed of timber, and are lined throughout with asbestos lining 23.

The roof 4 is provided with a manhole 24 to afford admission to the steam chest for the purpose of repairing and the like, the manhole 24 having a cover 25 provided with suitable locking means.

35 *Steam pipe system.*

The steam chest is heated by systems of steam coils, one system 26 along each of the side walls 2 and composed of parallel running pipes 27, the inlet 28 of which is disposed at the upper front end of the chest and the exhaust 29 of which is disposed at the lower rear end of the chest, the parallel pipes 27 of each system 26 being in communication with one another by a connecting vertically disposed header 30, one at each end of each system 26 to form a continuous passage from inlet to exhaust. Along the floor of the chest are disposed two other systems of steam coils, one in a plane parallel 50 with and above the other, each system being composed of parallel longitudinally running pipes 31 in communication with one another by headers 32, one at each end, and having an inlet 33 at the front end and at 55 one end of the headers 32 and an exhaust 34 at the rear end of the chest and at one end of the other headers 32, the headers 32 and the pipes 31 forming a continuous passage for each system. Through these steam systems, live steam is fed as the cooker requires a very high temperature, generally about 240° F., the chest being heated by these systems of steam pipes.

Below the steam pipes 31 there is provided an H-shaped perforated steam pipe

system having two parallel pipes 35, see Fig. 4, and an intermediate connecting pipe 36, the intermediate pipe being connected with a feed pipe 37. The perforations in the pipes 35 and intermediate pipe 36 are preferably staggered with respect to one another so as to distribute the steam in all directions throughout the chest. Steam fed into the chest aids in maintaining the proper temperature.

To the roof 4 along each side wall 2 are provided clips 38, see Fig. 2, to which the hangers 39 are secured, the hangers maintaining in alignment and supporting the parallel series of pipes 27.

The pipes 31 along the floor are practically inclosed in a chamber having a roof 40 composed of two plates 41 said chamber having end openings adjacent the front and the rear end of the steam chest and the plates meeting one another at the middle of the chest at which portion each plate is provided with a semi-circular recess 42, the two recesses together forming a circular opening across which a spider 43 is secured having a central bearing for a vertical stub shaft 44, the shaft extending below the spider 43 and having a fan 46 mounted upon its end. The shaft is provided with a sprocket 47 around which is passed a silent chain 48 passing through one of the side walls 2 and connected to driving mechanism, not shown, outside of the side wall 2. The fan in its operation draws the air from the chest down centrally through the opening formed by the recesses 42 and forces it through the heating chamber formed by the steam pipes 31 which reheated air then passes out of the end openings to return to the body of the steam chest.

To carry the cans through the cooker, a novel arrangement of conveyer is provided consisting of a winding track and a cable traveling therein, which conveyer is mounted on a frame work 49 adapted to be bodily removed from the steam chest through either of the doors 9 or 13 when desired, being shiftably mounted for that purpose. The frame work comprises two lower side rails 50 spaced apart and secured to one another by yokes 51, and upper side rails 52 which are spaced apart and secured to one another by yokes 51'. The side rails 52 are spaced apart from and supported above the side rails 50 by means of inner and outer posts 53 and 54. The frame work 49 is supported and carried on rollers 55 mounted on transversely disposed shafts 56, a series being provided and carried in brackets 57 of the lower yokes 51 and at each side thereof by means of which rollers the frame work may be rolled into or out of the steam chest 1.

The inner and outer posts 53, 54 at the upper front end of the frame work 49 are provided with a bearing bracket 58, the bear-

ing 59 of which bracket is in alinement with a bearing 60 in the casting 61 which is secured to the yoke 51 at the lower front end of the frame 49, in which bearings 59 and 60 is supported a shaft 62. The casting 61 is also provided with a bearing 63 extending horizontally and longitudinally of the frame work 49 and adapted to carry the driving shaft 64 upon which is mounted, outside of the door 13, the tight and loose pulleys *b* and *c*. At the extreme front end of the casting 61 is formed a bearing 65 for a stub shaft 66 to carry the feeding sprocket 67. To rigidly secure the frame work 49 in the steam chest 1, there are provided adjusting screws 68 which pass through the side walls 2 and bear against the outer sides of the upper ends of the outer posts 54. The posts 53, 54 at the upper rear end of the frame work 49 are provided with a bearing bracket 70, the bearing 71 of which is in alinement with the bearing 72 in the bottom casting 73 secured to the yoke 51 at the lower rear end of the frame work 49, the bearings 71 and 72 carrying the shaft 74.

Adjacent the plates 41 of the roof 40 and alongside each of the walls 2 beams 75 are secured on which angle irons 76 are fastened to serve as brackets for the rollers 55 of the conveyer frame.

The transversely parallel inner and outer posts 53 and 54 are fastened to one another at the top by the yokes or spacers 51'. On the outer sides of the posts 53 are provided lugs 78. The outer posts 54 are provided with small lugs 79 on their inner sides; one opposite each of the lugs 78. At various intervals throughout the frame work, ties may be provided between the adjacent posts 53 and 54 to secure them in alinement. On the lugs 78 on each side of the chest 1 angle irons 81 are fastened to the post 53 by means of bolts 80, which angle irons do not turn at the ends of the chest. Similarly angle irons 82 are provided along each side wall of the chest 1, which angle irons are fastened to the posts 54 above the lugs 79 by similar bolts 80, which angle irons likewise do not turn at the ends of the chest so that they together form track sections on each side of the chest, but terminating near the ends of the chest one above the other.

At each end of the chest and forming continuations of the angle irons 82 there are provided curved sheets 83 which are detachably mounted by means of slotted connections and pins *a* upon uprights 83', secured to the ends of the angle irons 82, the sheets 83 serving to connect the angle irons 82 of the two sides of the chest with one another to form a continuous outer wall for a winding track. It will be seen by reference to Figs. 1, 2 and 3 that a winding track is formed by the track sections 81, 82 in conjunction with the semi-cylindrical sheets or

turns 83; a side section of the track, as seen at 81, 82 in Figs. 1, 2 and 3 starting at the lower left hand end or entrance of the chest and extending to the other end of the chest with a gradual upward inclination to the 70 semi-cylindrical sheet or turn 83 at such other end of the chest, said winding track then turning around; the turn being formed by the inside of the sheet 83; the track continuing thence by the upwardly inclined side sections 81, 82 on the other side of the chest and returning to the left hand end of the chest; the winding track there being continued around by the semi-cylindrical sheet 83 at said left hand end of the chest and thereby connecting with the next higher side sections 81, 82 of the track which has an upward inclination along the side of the chest; and so on from semi-cylindrical sheet to semi-cylindrical sheet until the winding 85 track reaches the upper right hand end or exit of the chest.

The shafts 62 and 74 are provided with sheaves 84 which are spaced from one another by collars 85, the lowermost collar on the shaft 74 and gear 92 on the shaft 62 resting on thrust bearings 86 positioned on the bearings 72 and 60 respectively to receive the end thrust of the shafts and support the sheaves 84 and collars 85. On the 95 shaft 62, the upper sheave 84 is fixed to rotate with the shaft 62 by means of set screws 84' to thereby drive a cable 88. All the sheaves may be fixed to rotate with the shafts if desired by providing each with a 100 set screw. In the present instance only the upper sheave 84 on the shaft 62 is fixed to rotate with such shaft.

The sheaves are each provided with a groove 87 in which the cable 88 is adapted to travel, the peripheral ridge 89 of which sheaves below the groove 87 extending out farther than the peripheral ridge 90 above the groove 87, the extended ridge serving as a supporting surface for the cable. On the upper face of each of the sheaves inwardly of the ridge 90 is provided a crown *d*, which crowns at the turns of the tracks form the continuations of the inner walls of the track sections 81, the upper faces of the sheaves 115 outwardly of the crowns forming a platform or floor 91 for the track around such turns.

The shaft 62 is driven by the shaft 64, the shaft 62 having the gear 92 fixed to it and below its lowermost sheave 84, which gear 92 120 is in mesh with a worm 93 on the shaft 64.

The path of the continuous cable 88 of the conveyer is as follows: Around the feeding sprocket 67 in the casting 61 in the direction of the feathered arrows, longitudinally 125 through the chest along the lowermost side sections 81, 82 of the track and around the lowermost sheave 84 on the shaft 74, then around the sheave 84 and to the front end of the chest along the next upwardly in- 130

- clined side section of the track up to the lowermost sheave 84 on the shaft 62, and so on up to and around the uppermost sheave 84 on the shaft 62, whereupon it takes an inward direction, (see Fig. 5) around the idler 94 mounted on the vertical stub shaft 95 secured in the bracket 96, then around the idler 97 of a take-up device, then through the telescopic guide-way 98 around the idler 99 at the lower end of the telescopic guide-way, around an idler 77, (see Fig. 3) mounted upon a stub shaft 95' carried by a bracket 96' of the casting 61 and thence to the sprocket 67, thus making a continuous path.
- 15 The telescopic guide-way consists of an upper section 100 mounted to slide in the lower section 101. The upper end 102 of the upper section 100 has a slight outward flare as it curves one-quarter of a revolution around the idler 97, brackets 103 being secured around each side of the upper section 100 which brackets are mounted upon a shaft 104 radially inward of said upper end on which shaft the idler 97 is mounted.
- 20 The shaft 104 is carried by side rollers 69 running upon a track 771 secured to the frame work 49 at each side of the take-up and extending longitudinally of said frame work to act as a horizontal guide for the upper end of the telescopic guide-way. Connected to the shaft 104 is a yoke 105 to the end of which is secured a cable 106, which extends longitudinally toward the rear of the chest 1 where it passes over an idler 107 mounted on a shaft 108 secured to the frame work 49 in the chest, the cable 106 having a weight 109 secured to its end, by means of which the cable 106 exercises a continual pull on the top of the telescopic guide-way
- 25 98 to move the shaft 104 along in the track 771 and thereby draw the guide-way 98 toward it and by so doing first sliding the section 100 into the section 101 when it is forward of its vertical position and sliding the section 100 out of the section 101 when the guide-way inclines rearward of its vertical position. In this way the slack in the cable 88 will be taken up. The lower end 110 of the lower section 101 is similarly curved
- 30 one-quarter of a revolution around its idler 99, the brackets 111 being secured around each side of the lower section 101 and supporting a shaft 112 between them on which the idler 99 is mounted, the shaft 112 being
- 35 mounted in bearing brackets 113 secured to the set of posts 53, in the present instance the second set of posts from the front of the chest. By reference to Fig. 1, it will be seen that the idlers 97 and 99 operate in a plane that lies longitudinally of the chest 1 and between the two directions of tracks.
- The sections 100 and 101 form guide-ways for the cable, said guide-ways comprising two inclined side sheets 114 extending upward and outward away from the floors
- 40 of the sections and secured to the floors of the sections respectively.
- The cans 115 to be carried through the cooker are placed on their sides and carried by the cable 88, the cans being spaced apart from one another by means of pins 116 which are fastened to the cable at equal intervals along the same. To accommodate the pins 116 when passing around the various sheaves and idlers, these sheaves and idlers are provided with recesses 117 spaced apart a distance corresponding to the distance between two successive pins 116.
- 45 At the entrance to the chest 1 there is provided a special feeding sprocket 67 which co-operates with a tunnel 118 to feed in one can between each two successive pins 116. The tunnel as illustrated in Figs. 1, 2 and 3 has supporting irons 119, one secured to each straight side 19 of the entrance chute, the two irons 119 supporting between them the stationary hood 120, the forward end of the roof 121 of said hood 120, being provided with a hinge 122 to which a movable hood 123 is hinged, having straight sides 124, an upwardly inclined roof portion 125 extending forward and upward a short distance from the hinge 122 and having a floor 126 that is parallel to the short roof portion 125 and spaced apart from the roof portion just sufficient to permit a can to pass between the two, a substantially horizontal floor portion 127 being united with the floor portion 126 which floor 127 contacts with the lower edge 128 of the opening 21 whereby the tunnel 118 is supported when in feeding position. The sprocket 67 has an internal sheave member 129 formed substantially like the sheaves 84 having recesses 117 for the pins 116, the ridges 130 on each side of the cable-receiving groove 131 being practically equal. On each side of the sheave member 129 is secured a feeding sprocket disk 132. The sprockets of the two disk members are parallel with one another, and have a forward face 134 that is concave and a rear face 135 that is convex, the arrangement of sprocket disks 132 relative to the sheave member 129 being such that each pin 116 of the conveyer cable 88, will, as such pin 116 passes around on the sheave member 129, project out just rearwardly of a concave face 134 and alongside of a convex face 135 so that a can 115 may be received by the two parallel concave faces 134 with a pin 120 116 engaging the can 115 at its rear by means of which the cans will be passed on to the track with a conveyer cable pin 116 at its rear. The sprocket 67 and tunnel 118 prevent piling up of the cans onto the conveyer cable and track since only one can may pass between the inclined floor 126 and roof 125 before the next succeeding can 115 is permitted to pass onto the concave faces 134, the convex faces 135 projecting outward 130

rise above the floor 126 and hold the succeeding can on the floor 126 until the succeeding concave faces 134 rise up.

The forward portion of the tunnel 118 is pivoted about the hinges 122 so as to be raised, after the cover 20 has been opened by means of which ready access is permitted to the feeding sprocket 67 and thereto connected parts.

- 10 The cable is arranged to travel just under and between the side rails of the track with the cable pins 116 extending up between the horizontal legs of the track rails 81, 82 to roll the cans along said legs, see Figs. 6 and
- 15 7, and in the present instance the pins 116 comprise similar half sections, each of which has a cable gripping groove 137, said sections being gripped in position upon the cable by means of upper and lower bolts 139, the upper bolt passing through cable supporting lugs 138 upon the outside of each of the pin sections. As the cable moves
- 20 along between the rails it is supported by these lugs 138 which slide upon the horizontal legs of the side rails 81, 82 during the course of travel. On the pins 116 are provided shoulders 140 to prevent any upward movement of the pins, which shoulders together with the lugs 138 maintain the
- 25 cable in accurate alinement with the end sheaves.

In the operation of the device, it will be seen that the cans passed in at the entrance will each be secured between two pins 116, 35 the cans lying on their sides upon the horizontal legs of the tracks so that they may be rolled therewith by the tips 141 of the pins to agitate the food stuffs contained therein, the side walls of the tracks between 40 which the cable passes serving as guides to maintain the cans in position over said cable.

The opening 12 at the upper end of the door 9 serves as an exit or discharge for the 45 cooker. The opening 12 is positioned above the curved sheet 83 and opposite the topmost sheave 84 so that a chute 142 may be secured adjacent the topmost sheave 84 and supported on the lower edge of the opening 50 12 to receive the cans passing on to the topmost sheave 84 and feed them out through the discharge opening 12. The chute 142 has side walls 143 and a sloping floor 144 fastened to the side walls, the inner one of 55 said walls being provided with a side opening 145 through which the cable pins pass upon their way out of the chute and around the topmost sheave 84. A portion of the top floor is cut away to accommodate the topmost sheave 84, leaving the aslant edge 146 which extends from the side opening 145 at one side to the abutting track angle 82 at the other side.

When the food stuffs being cooked do not 60 require to be passed through the entire

cooker, the cans containing such food stuffs may be switched off or discharged from any one of the lower sheaves according to the length of time the food stuffs require to be cooked. For this purpose the curved sheet 70 83 may be provided with openings 147 one above the other and each opposite a sheave 84, as shown at the right of Fig. 1. Opposite these openings 147 the door 9 is provided with discharge openings 148 similar 75 to the discharge opening 12 already described, and when it is desired to discharge the food stuffs through one of these lower sets of openings, it is only necessary to secure a chute similar to the chute 142 in 80 place through such set of openings. The discharge openings 147 and 148 are provided with doors 149 and 150 respectively, composed of substantial material and suitably lined, the doors being fastened in place 85 when desired by any suitable means such as the studs 151.

It is obvious that various changes and modifications may be made to the details of construction without departing from the 90 broad scope of the invention.

I claim:

1. In a cooker, the combination with a heat-containing chest, of a frame-work adapted to be moved into said chest, steam coils secured in said chest, a conveyer operatively mounted on said frame-work to convey the substance to be cooked through said chest, plates secured in the chest below said frame-work, said plates forming three 95 openings, one in the middle and one at each end of the chest, and means to draw the atmosphere in said chest down through said middle opening and underneath said plates, the atmosphere being permitted to rise 100 through the end openings.

2. In a cooker, the combination with a heat-containing chest, of a winding endless conveyer for carrying cans through said chest, and pins extending upward from said conveyer to engage the cans carried on said conveyer and space them apart from one another, said pins being provided with means to prevent lateral and vertical movement of the conveyer.

3. In a cooker, the combination with a heat-containing chest, of a winding track comprising side rails spaced apart from one another, sheaves at the turns of said track, curved sheets connecting together the adjacent ends of adjacent rails, and an endless cable traveling between said side rails and around said sheaves for carrying cans through said cooker.

4. In a cooker, the combination with a heat-containing chest, of a winding track comprising side rails spaced apart from one another, curved sheets connecting together the adjacent ends of adjacent rails, sheaves at the turns of said track, said sheaves being 125 130

- provided with crowns to form continuations of the inner walls of the rails, an endless cable traveling between said rails and around said sheaves for carrying cans through said chest, 5 and pins extending upward from said cable to engage the cans to move the same and space them apart from one another.
5. In a cooker, the combination with a heat-containing chest, of a winding track 10 comprising side rails spaced apart from one another, sheaves at the turns of said track, said sheaves being provided with crowns to form continuations of the inner walls of the rails, an endless cable traveling between 15 said rails and around said sheaves for carrying cans through said chest, and pins extending upward from said cable to engage the cans and space them apart from one another, there being notches in said sheaves 20 spaced apart from one another to each admit a pin of said cable as the pins travel around said sheaves.
6. In a cooker, the combination with a heat-containing chest, of a winding track removably secured in said chest, said track comprising side rails spaced apart from one another, sheaves at the turns of said track, said sheaves being provided with crowns to form continuations of the inner walls of the rails 25 and being provided with upper faces outwardly of said crowns to form the floor of the track, an endless cable traveling between said side rails and around said sheaves for moving cans along said track, the cans 30 lying on their sides on the track while passing through said cooker thereby to be rolled from side to side and agitate their contents, the tracks serving to guide the cans, and pins extending upward from said cable to 35 engage the cans to move them along and space them apart from one another.
7. In a cooker, the combination with a heat-containing chest, of a winding track arranged in said chest, the turns of said 40 track being arranged one above another, a cable traveling along said track for moving cans through said chest, the cans lying on their sides upon the track while being moved so as to agitate their contents, doorways 45 opposite the turns of said track, and discharge chutes to be secured from any level of track to the adjacent doorway whereby to discharge the cans from the level of the track to which the chute is secured.
- 55 8. In a cooker, the combination with a heat-containing chest, of a winding track arranged in said chest, the turns of said track being arranged one above another, said track comprising side rails, sheaves at the turns 50 of said track, a shaft at each turn of the track, said sheaves being mounted on said shafts, a cable traveling between said side rails and around said sheaves for moving cans through said chest, the cans lying on 55 their sides while being carried along said
- track so as to agitate their contents, doorways opposite the turns of said track, discharge chutes to be secured from any level of track to the adjacent doorway whereby to discharge the cans from the level of track to which the chute is secured, and means for driving one of said shafts, some of said sheaves being fixed to rotate with said driven shaft whereby the cable is moved along said winding track.
9. In a cooker, the combination with a heat-containing chest, of doors hinged to the roof one at each end of said chest, means for fastening said doors in closed position, a winding track removably secured in said chest and adapted to be moved out of said chest bodily through one of the ends of said chest, there being discharge openings provided in said hinged doors one adjacent each level of said winding track, and covers for said discharge openings to close those openings through which the cans are not being discharged.
10. In a cooker, the combination with a heat-containing chest, of a conveyer for carrying cans lying on their sides while passing through said chest, pins extending up from said conveyer to engage the cans and space them apart from one another, a hood for the entrance to said chest just sufficiently large to admit one can at a time, a feeding sprocket wheel co-operating with said hood over which the conveyer passes, said sprocket wheel receiving the cans from said hood and passing the same to said conveyer and said sprocket wheel having a forward concave face and a rearward convex face, the sprockets of said sprocket wheel blocking the opening from said hood immediately after receiving a can so as to feed but one can at a time to said conveyer, the pins of said conveyer being so arranged that each will project rearwardly of the concave face and alongside of the convex face and there engage the rear of the can received on said sprocket wheel from said hood.
11. In a cooker, the combination with a heat containing chest, of a frame-work within said chest, a conveyer operatively mounted on said frame-work to convey the substance to be cooked through said chest, a chamber positioned in the chest below the frame-work, steam coils mounted in the chamber, said chamber being provided with open ends and a central opening in its roof, and having a circulation fan mounted in said central opening to draw the atmosphere in said chest down through the opening into said chamber, the atmosphere being permitted to rise through said open ends.
12. In a cooker, the combination with a heat containing chest, of a winding track comprising angular side rails having adjacent horizontal legs spaced apart from one another, sheaves at the turns of said track,

an endless cable traveling between said rails and around said sheaves for conveying cans through said chest, and pins on said cable arranged to extend up between said horizontal legs to move the cans therealong, said pins being provided with side supporting lugs and adjacent shoulders, the lugs being adapted to ride upon the horizontal legs to support the cable and the shoulders being adapted to ride under the horizontal legs

to maintain the cable in alinement as said cable travels between the side rails.

In testimony whereof, I have hereunto set my hand at Los Angeles, California, this 21st day of May, 1914.

HENRY CLAUDE PRIVETT.

In presence of—

JAMES P. TOWNSEND.

J. W. WILLARD.
